US0D1103029S

(12) **United States Design Patent** (10) Patent No.: **US D1,103,029 S**
(45) Date of Patent: ** Nov. 25, 2025

(54) **VEHICLE FRONT BUMPER APPLIQUE**

(71) Applicant: **Ford Global Technologies, LLC**,
Dearborn, MI (US)

(72) Inventors: **Kemal Curic**, Lake Forest, CA (US);
Earl Lucas, Southfield, MI (US);
Darren Luke, West Bloomfield, MI
(US); **Benjamin Messmer**, Los
Angeles, CA (US)

(73) Assignee: **Ford Global Technologies, LLC**,
Dearborn, MI (US)

(**) Term: **15 Years**

(21) Appl. No.: **29/914,247**

(22) Filed: **Oct. 16, 2023**

(51) LOC (15) Cl. **12-08**

(52) U.S. Cl.
USPC **D12/190**

(58) **Field of Classification Search**

USPC D12/88, 164, 173, 182-183, 190-191,
D12/404; D14/172

(57) **CLAIM**

The ornamental design for a vehicle front bumper applique as shown and described.

DESCRIPTION

FIG. 1 is a front elevational view of a vehicle front bumper applique, showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a top, front and left side perspective view thereof; and,

FIG. 7 is a bottom, front and left side perspective view thereof.

The claimed design is indicated by the relatively dark portions in the figures. The de-emphasized and relatively light portions form no part of the claimed design.

1 Claim, 7 Drawing Sheets
